SHEET FEEDER

James R. Wood, Cleveland, Ohio, assignor to
 Harris-Seybold Company, Cleveland, Ohio, a
 corporation of Delaware

Application June 9, 1948, Serial No. 31,949

9 Claims. (Cl. 271—53)

1

This invention relates to improvements in sheet feeders, and has to do primarily with means for presenting accurately registered sheets to the grippers of a rotating cylinder, such as a cylinder of a rotary printing press.

In accordance with the present invention the functions of an intermittently operating transfer cylinder and those of a pair of over feeding nipper rolls are combined; that is to say a transfer cylinder having a stationary period, an acceleration period, a constant speed period and a decelerating period is arranged to transfer sheets one at a time to a continuously rotating cylinder, and is supplied with front stops against which the forward edge of each sheet after being preliminarily registered on a feed board is pressed by a pair of nipper rolls, the nipper rolls being driven from the transfer cylinder by continuously meshing gears and therefore partaking of the same periods. The gearing is so arranged however that the surface speed of the nipper rolls exceeds that of the transfer cylinder. The over feeding of the sheet against the stops on the transfer cylinder preferably takes effect during the said acceleration period, although it may take place during the constant speed period, and the transfer of the sheet from the transfer cylinder to a continuously rotating cylinder of the press takes place during the constant speed rotation of the transfer cylinder. The nipper rolls close upon the sheet when the rolls and the sheet are stationary and before the front guides are withdrawn, and because the nipper rolls accelerate gradually control of the sheet by the nipper rolls is accurately maintained until the sheet is grasped by the sheet grippers on the transfer cylinder. The drive of the nipper rolls is designed to provide a small degree of over feeding of the sheet against the rotating stops thereby ensuring the arrival of the sheet at the stops and the correction of any slight derangement of the front edge of the sheet which might occur during side-register thereof.

One of the objects of the invention therefore is the provision of an improved method and means for taking sheets from the forward end of a feed board and transferring them to grippers of a rotating printing press or other sheet handling machine.

Another object is the provision of a novel method and means for driving a pair of nipper rolls from an intermittently rotating transfer cylinder to provide gradual acceleration of the sheet and smooth and positive engagement of its front edge against stops on the transfer cylinder.

2

Other objects and features of novelty will appear as I proceed with the description of that embodiment of the invention which, for the purposes of the present application, I have illustrated in the accompanying drawings, in which

Fig. 1 is a diagrammatic side elevational view of sheet feeding means embodying the invention, the transfer cylinder and the nipper rolls being in their stationary period, and the nipper rolls being closed upon the sheet.

Fig. 2 is a fragmental plan view of the same.

Fig. 3 is a view similar to Fig. 1, but on a larger scale, showing the transfer cylinder and nipper rolls in the accelerating period and the sheet being taken by the transfer cylinder grippers.

Fig. 4 is a similar view showing the parts at the end of the constant speed period or the beginning of the deceleration period.

Fig. 5 is a similar view illustrating the beginning of the stationary period during which the sheet is front and side registered on the feed board preparatory to the closing of the nipper rolls.

Fig. 6 is a view similar to Fig. 3, but on a larger scale.

In the drawing the impression cylinder of a rotary offset press is indicated at 10. It represents a continuously rotating cylinder, which may be termed a sheet advancing cylinder, adapted to present sheets to the impression cylinder. An intermittently rotating cylinder 12 arranged to take sheets from a feed board 13 is driven from cylinder 11, the mechanism being such as to provide a stationary period, an accelerating period, a constant speed rotation period and a decelerating period, the driving mechanism for the purpose being known in the art and fully described in Patent No. 2,192,908 to Harrold et al. Drive may be supplied to cylinder 11 by a small gear 14 meshing with gear 15. Gear 15 in turn meshes with gear 16 on cylinder 10, and intermittently with a segmental gear 17 on cylinder 12. The pitch lines of gears 15, 16 and 17 conform with the surfaces of the corresponding cylinders. While I have termed these members cylinders, it will be understood that their cylindrical surfaces may be interrupted so long as proper support for the sheets is provided.

During a portion of each revolution of cylinder 12, gear 17 meshes with gear 15 and the two cylinders 11 and 12 turn at equal surface speeds. During the time that the gears 15 and 17 are out of mesh cylinder 12 decelerates, stops and accelerates. The transition from acceleration to constant speed rotation is effected smoothly.

The illustrated mechanism for driving cylinder 12 will now be briefly described.

20 is a bracket which turns with cylinder 11. On its inner side it carries two rollers 21 and 22, and on its outer side it carries two other rollers 23 and 24. Rollers 21 and 22 engage at times with the side edges of a fishtail cam 25 which is mounted to turn with the shaft of cylinder 12. A pair of cams 26 and 27 fixed upon cam 25 have internal edge surfaces with which the rollers 23 and 24 engage.

In Fig. 1 the acceleration period is beginning, that is roller 21 has come into engagement with an outer end of fishtail cam 25, and as the roller travels downward it rides inwardly along the cam, thereby gradually increasing the speed of the cam and hence of the cylinder 12. During this time roller 23 by engaging cam 26 holds the cam 25 against the roller 21 and prevents rotation of cylinder 12 faster than intended. When the roller 21 reaches the inner end of the cam 25 the cylinder 12 will have been accelerated to the same surface speed as cylinder 11, and gear 17 will then have been brought into mesh with gear 15, so that cylinder 12 will turn at the same surface speed as cylinder 11.

The period of constant speed rotation continues until the arc 28 of gear 17 which is devoid of teeth again comes into the line of centers of gears 15 and 17, at which time roller 22 will be engaged by the opposite side edge of fishtail cam 25, as illustrated in Fig. 4. At this time the roller and cam are turning at equal speed, but as the roller travels downwardly or counterclockwise it moves outwardly along the cam surface or away from the center of revolution of the cam, and thereby decelerates the cam and the cylinder 12. During this deceleration period the roller 24 running upon cam 27 maintains the fishtail cam in contact with roller 22.

At the point in the cycle illustrated in Fig. 5 of the drawing the cam 25 and the cylinder 12 have been decelerated to zero speed and the rollers 22 and 24 are leaving the cams 25 and 27. Also at this point a block 30 has entered a socket or recess 31 in a disk 36 which rotates with gear 17 to hold cylinder 12 against accidental movement during the stationary period. The stationary period continues until roller 21 travels from the position illustrated in Fig. 5 to that illustrated in Fig. 1. Block 30 is carried on a bell crank 32 pivoted at 33 to the frame of the machine, the other arm of the bell crank carrying a follower 34 which runs upon a cam 35. This cam has continuous rotation in one to one ratio with cylinders 10 and 11. The follower 34 is held against the cam by suitable spring means, not shown. At about the time the roller 21 engages cam 25 follower 34 rides down off the high spot of cam 35 and the block 30 releases its hold upon cylinder 12.

37 is a shaft journaled in the frame of the machine somewhat above cylinder 12 and to the rear of its axis. Shaft 37 carries a series of disks 38, which together constitute a nipper roll. Shaft 37 also carries a gear 39 which meshes with a gear 40 keyed to the shaft of cylinder 12. Gear 40 is of greater diameter than gear 17, so that disks 38 are driven at greater surface speed than they would be if gear 39 were meshed with gear 17. A lower nipper roll 41 is built in spaced sections which are adapted to contact disks 38 through suitable slots in feed board 13. The spaced sections of nipper roll 41 are carried upon the extremities of arms 43 keyed to shaft 44 pivoted in

the frame and carrying a lever 43' having a follower 45 at its lower end which runs on a rotating cam 46 that also turns in one to one ratio with cylinders 10 and 11. It will be apparent therefore that during a sort interval of each cycle nipper roll 41 is raised to press a sheet against disks 38 of the upper nipper roll. This interval begins at about the end of the stationary period of cylinder 12, as illustrated in Fig. 1, and continues into the acceleration period as illustrated in Fig. 3.

Sheets may be brought down onto feed board 13 singly or in a stream by traveling tapes 48. Front guides 49 of conventional character are clamped to a rock shaft 50 journaled in the frame and oscillated by known means to bring the guides into the path of the sheets traveling over the feed board at the proper time in the cycle. In Figs. 1 and 5 they are illustrated in operative position. The side registration of each sheet directly after it is front registered is contemplated, but as mechanism for accomplishing side registration is well known in the art no mechanism for that purpose is illustrated herein.

25 Cylinder 12 carries a series of front stops 52 against which the forward edge of each sheet is to be pressed by the nipper rolls. Cylinder 12 also carries a rock shaft 53 upon which are fixed gripper fingers 54 that cooperate with gripper pads 55. Shaft 53 is actuated at properly timed intervals to swing grippers 54 into gripping relation with pads 55 for grasping the forward edge of a sheet, and at other intervals to swing away from the pads for releasing the sheet. The grippers 30 may be operated by conventional means not herein shown.

Sheet advancing cylinder 11 and impression cylinder 10 are also provided with sheet grippers 56 and 57 respectively, grippers 56 taking a sheet 40 from grippers 54 and presenting it to grippers 57, as will be obvious to those skilled in the art.

In order to insure the engagement of the forward edge of each sheet with the front stops 52 on cylinder 12 I may provide a guard 60, illustrated in Fig. 6, consisting of a series of flat metal fingers shaped to conform closely to the contour of the feed board 13 and cylinder 12 and carried upon a shaft 61 which extends across the machine above cylinder 12. In practice the guard 60 is raised slightly during the greater part of each cycle and is lowered to the illustrated position just prior to the time each sheet is fed forward by the nipper rolls. The relative speeds of the nipper rolls and the cylinder 12 are such that a small buckle tends to be formed behind the front stops 52, but the guard 60 controls this buckle and prevents its assuming too short a curvature.

Operation.—A sheet coming down the feed board 13 is front registered against front guides 49 and is then side registered in the conventional manner. This occurs as soon as possible after the preceding sheet has passed the front guides 49. As soon as registration is completed, 65 and toward the end of the stationary period of cylinder 12, cam 46 acts upon lever 43' to close the nipper rolls against the registered sheet. Immediately thereafter cam 35 permits block 30 to move out of socket 31, thereby unlocking cylinder 12. Roller 21 then travels downwardly against fishtail cam 25, accelerating cylinder 12 and the upper nipper roll. Before acceleration begins the sheet is firmly in the grasp of the nipper rolls. Their acceleration is smooth and gradual, so that there is no tendency to jerk the 70 75

sheet out of its registered relation to its path of movement. Gear 40, being larger than gear 17, drives the nipper rolls at a faster surface speed than the stops 52, and consequently during the acceleration period the forward edge of the sheet is pressed against the stops as shown in Fig. 3, where the sheet is marked S. Immediately thereafter, before the nipper rolls are opened by the movement of cam 48, the sheet grippers grasp the forward edge of the sheet and carry it forward. The speed of the grippers at the time they close upon the sheet may be of the order of one-half or two-thirds of the surface speed of cylinders 11 and 10. During its forward travel over cylinder 12 the sheet may be held in engagement with the surface of that cylinder by suitable means, such as by brushes 59. Before grippers 54 reach the line of centers of cylinders 12 and 11 cylinder 12 will have been accelerated to the same surface speed as cylinder 11, so that transfer of the sheet to grippers 56 is accomplished accurately and without damage to the sheet.

Having thus described my invention, I claim:

1. Mechanism for feeding sheets to a printing press or other sheet handling machine, comprising a continuously rotating cylinder, a transfer cylinder in sheet transferring relation therewith, front stops on said transfer cylinder, driving connections between said cylinders for causing said transfer cylinder to have a stationary period, an acceleration period, a period of constant speed rotation at the surface speed of said continuously rotating cylinder and a deceleration period, nipper rolls for over feeding sheets to said transfer cylinder stops, continuously meshing gearing connections between said transfer cylinder and one of said nipper rolls for driving said last named nipper roll at a surface speed above that of said transfer cylinder, and intermittently acting means for exerting tractive force between said last named nipper roll and a sheet to be fed.

2. Mechanism as defined in claim 1, comprising means for causing said nipper rolls to advance the sheet during the said acceleration period.

3. Mechanism as defined in claim 2, comprising front guides disposed forward of the bite of said nipper rolls, and means for causing said nipper rolls to close on the sheet during said stationary period after the sheet is registered against said guides.

4. Mechanism as defined in claim 1, wherein said gearing connections comprise a gear on said transfer cylinder of greater diameter than said transfer cylinder, and a gear on one of said nipper rolls meshing with said transfer cylinder gear.

5. Mechanism for feeding sheets to a printing press or other sheet handling machine, comprising a continuously rotating cylinder, a transfer cylinder in sheet transferring relation therewith, front stops on said transfer cylinder, driving connections from said continuously rotating cyl-

inder for causing said transfer cylinder to have acceleration and deceleration periods with an intermediate period of constant speed rotation equal in surface speed to the surface speed of said continuously rotating cylinder, nipper rolls for over feeding sheets to said transfer cylinder stops, continuously meshing gearing connections between said transfer cylinder and one of said nipper rolls for driving said last named nipper roll at a surface speed above that of said transfer cylinder, and means for moving the other nipper roll into position for exerting tractive force against the sheet to be fed during said acceleration period.
